TYING PLATE FOR CONVEYERS

Ernest C. Barker, Oak Park, Ill., assignor to The Gerrard Company, Inc., Chicago, Ill., a corporation of Delaware

Application September 13, 1940, Serial No. 356,574

4 Claims. (Cl. 193—35)

This invention has to do with conveyers of the type commonly used in factories, shipping rooms and similar places for moving objects of various sorts from one point to another.

The purpose of the invention is to provide means, in the nature of a novel tying plate, for releasably connecting two conveyers together in end-to-end relation, in such manner as to form a bridge-like structure between the conveyers across which objects can travel without difficulty.

While the foregoing statement is indicative in a general way of the nature of the invention, other more specific objects and advantages will be apparent to those skilled in the art upon a full understanding of the tying plate and the way in which it is intended to be used.

A preferred embodiment of the invention is presented herein for the purpose of exemplification, but it will of course be appreciated that the invention is capable of embodiment in other structurally modified forms coming equally within the scope of the appended claims.

In the accompanying drawing:

Fig. 1 is a perspective view which shows two roller conveyers connected together in end-to-end relation by a tying plate constructed in accordance with the invention;

Fig. 2 is a plan view of the tying plate and conveyers;

Fig. 3 is a vertical longitudinal section, taken on the line 3—3 of Fig. 2; and

Fig. 4 is a vertical transverse section, taken on the line 4—4 of Fig. 2.

Referring to the drawing, it will be observed that the tying plate 10 is adapted to provide a connection between two roller conveyers 11. The conveyers 11 are provided at regular intervals with anti-friction rollers 12, and the rollers 12 are journaled at their ends in apertures in suitably supported side rails 13. The plate 10, which is preferably of one-piece sheet metal construction, is provided with a flat top 14, two down-turned side flanges 15 and two downwardly curved end flanges 16. The side flanges 15 are preferably spaced apart substantially the same distance as the side rails 13 of the conveyers, in endwise alignment with the side rails, and the end flanges 16 terminate laterally short of the ends of the side flanges 15 and extend downwardly in a curve of substantially the same radius as the rollers to a point just below the level of the axes of the rollers. These end flanges 16 hook about the end rollers 12 on both conveyers, and can be quickly and easily applied or removed. The ends of the side flanges 15 are spaced far enough from the ends of the side rails 13 of the

conveyers to allow the conveyers to be moved slightly towards each other, whereby to permit vertical movement of the plate when hooking or unhooking the same. When in position the plate interlocks the conveyers in end-to-end relation and provides a bridge over which articles moving along the conveyers can easily pass.

I claim:

1. In a conveyer assembly, the combination with two conveyers of the type provided with rollers, of a tying plate for said conveyers characterized by a substantially flat generally rectangular load supporting top of one-piece sheet metal construction, and downwardly curved integrally formed end flanges on said top for detachably hooked engagement with the end rollers of said conveyers, with the top of the plate approximately flush with said end rollers.
2. In a conveyer assembly, the combination with two conveyers of the type provided with side rails and rollers, of a tying plate for said conveyers characterized by a substantially flat generally rectangular load supporting top of one-piece sheet metal construction, downwardly curved integrally formed end flanges on said top for interlocking engagement with the end rollers of said conveyers, and down-turned integrally formed side flanges on said top in substantial alignment with the side rails of the conveyers.
3. A tying plate for roller conveyers of the type having side rails, characterized by a substantially flat generally rectangular load supporting top of one-piece sheet metal construction, downwardly curved integrally formed end flanges on said top for interlocking engagement with the end rollers of adjoining conveyers, and down-turned integrally formed side flanges on said top in substantial alignment with the side rails of the conveyers, the lower edges of said downwardly curved end flanges terminating below the level of the axes of the rollers in closely conforming association with the latter, and the ends of said down-turned side flanges terminating in slightly spaced relation to the ends of the side rails of the conveyers.
4. In a conveyer assembly, the combination with two conveyers of the type provided with rollers, of a tying plate for said conveyers characterized by a generally rectangular load supporting top, said top having hook-shaped end portions adapted to rest upon the end rollers of said conveyers in detachably hooked engagement with the end rollers, with the top of the plate approximately flush with said rollers.

ERNEST C. BARKER.
